UNITED STATES PATENT OFFICE.

JOSEP LEWANDOWFSKI, OF ALLEGHENY, PENNSYLVANIA.

CARPET-CLEANING MACHINE.

SPECIFICATION forming part of Letters Patent No. 739,611, dated September 22, 1903.

Application filed March 23, 1903. Serial No. 149,035. (No model.)

To all whom it may concern:

Be it known that I, JOSEP LEWANDOWFSKI, a citizen of the United States of America, residing at Allegheny, in the county of Allegheny and State of Pennsylvania, have invented certain new and useful Improvements in Carpet-Cleaning Machines, of which the following is a specification, reference being had therein to the accompanying drawings.

This invention relates to certain new and useful improvements in carpet-cleaning machines; and the object of the invention is to provide a simple, cheap, and effective machine adapted either for household use or for carpet-cleaning establishments, though particularly adapted as a small machine for household use.

Another object of the invention is to construct a machine of this type which when not in use may be folded in such a manner as to occupy but comparatively little space; to provide means for supporting the carpet in such position that it may be readily drawn underneath the beaters to be engaged thereby; to provide a series of beaters to clean the carpet as it is drawn underneath the beaters; means for operating said beaters; means for holding the beaters normally inoperative when desired, and other features of construction, as will be hereinafter more specifically described and then particularly pointed out in the appended claims.

In describing the invention in detail reference will be had to the accompanying drawings, forming a part of this application, and wherein like numerals of reference will be employed for indicating like parts throughout the different views of the drawings, in which—

Figure 1 is a detail top plan view of my improved carpet-beating machine in the extended position. Fig. 2 is a side elevation of the same. Fig. 3 is a cross-sectional view taken on the line 3-3 of Fig. 1 looking in the direction of the arrow. Fig. 4 is a like view taken on the line 4-4 of Fig. 1 looking in the direction of the arrow. Fig. 5 is a detail side elevation of the machine in the folded form.

To put my invention into practice, I provide a pair of standards or housings 1, mounted on pedestals or bases 2, in one end of which are placed rollers 3, the other ends of the pedestals

or bases being adapted to engage directly with the floor. The pedestal or base of each standard is connected to the other by a cross-brace 4, and at the upper ends of the standards or 55 housings they are connected by a brace 5. The standards or housings are provided on their forward edge or face with bearings 6, in which is journaled the beater-actuating shaft 7, provided with cams or knockers 8, staggered 60 on the shaft, there being two cams or knockers for each beater, whereby each beater is actuated twice with one revolution of the shaft 7. For a small machine adapted for household use the shaft may be driven by means of a 65 crank 9 on one end thereof, and if a large machine is to be built for factory purposes a belt-pulley may be substituted for the crank, whereby the shaft may be operated by steam or other power. The standards or housings 70 are also provided on their rear edges or faces with bearings 10, in which is journaled a shaft 11, which carries the beaters. These beaters are each made in two sections or members, the section or member 12 being mounted on 75 the shaft 11 and the section or member 14 being detachably secured to the section or member 12. This is preferable in order that if one of the beaters be broken a new one may readily be placed in position without requiring the necessity of disconnecting the member or section 12 of the beater from the shaft 11. A convenient method of securing the sections or members together is by providing 80 a headed stud or pin 16 on the sections or members 12 and providing the ends of the sections or members 14 with a notch 17 to receive said headed stud, pin, or screw 16. A bolt 18 is passed through the two sections near the ends of the sections 12 and preferably secured by 85 a winged nut 19, as shown.

The beaters are pulled down by the action of springs 20, connected at their upper ends to the sections or members 12 of the beaters and at their lower ends connected to a tension-regulating bar 21, pivoted or hinged at its one end to the standard or housing base, the opposite end of this bar being under the tension of a spring 22. This spring 22 is arranged on a bolt 23, carried by the pedestal or base 2, and provided on its upper end with a winged nut 24, which when turned down forces the bar 90

21 downwardly, compressing spring 22 and increasing the tension of springs 20. The beaters may be held in the normally elevated position whereby to permit the insertion of the carpet into position or the removal of the same by means of a presser-bar 25, carried on a rod or stem 26, which extends through the top cross-bar 5 and is pivotally connected to a lever 27, pivoted at 28 to said top cross-bar 5. This lever carries a hook 29, adapted to be engaged with an eye 30, carried by one of the standards or housings for holding the presser-bar depressed in engagement with the beaters and the latter elevated. This presser-bar is held normally elevated by means of a spring 31, arranged on the stem 16, between the cross-bar 5 and a shoulder 32 on said stem, the stem being connected to the lever by means of a small link 33.

20 The carpet to be cleaned is supported in position for engagement by the beaters on a foldable frame, so connected to the standards or housings as to be moved into horizontal position for use and when not in use to be folded up against the housings or standards. To this end each side rail of the frame is constructed in two sections or members 34 35, hinged together, as at 36, and when in the extended alined position, as shown in Figs. 1 and 2, held by means of clips 37, carried by the sections or members 34. These clips or keepers are provided with slots 38 to receive headed studs or pins 39, on which the keepers or clips slide, the said clips or keepers spanning the joint when the rails are alined.

35 The sections or members 34 of the side rails are provided with slots 40, which receive bolts 41, carried by the standards or housings and have winged nuts 42, adapted to impinge against the outer face of the sections 34 and hold the rails in the position to which they have been adjusted. Means is provided at each side of the frame for supporting the carpet to be cleaned. To this end I secure to each of the sections 35 of the side rails a foldable supporting - frame embodying transversely-extending bars 43, pivoted at their inner ends to the sections or members 35 of the side rails, and at their outer ends pivotally connected to a bar 44. To the central one of the bars 43 is attached pivotally, in order that it may fold, a supporting-leg 45. When in the extended position this supporting-frame is held by suitable means, such as by a hook 46, secured to the section 35 of the side rails and engaging in an eye 47, carried by the outside bar 43. On top of the sections or members 35 of the side rails are placed rollers 48, across which the carpet is drawn, and the carpet is supported between the side rails whereby to be engaged by the beaters on a flexible bed, preferably composed of a series of cords 49, stretched across from one side rail to the other. For this bed I have found cords to be the more preferable, as in event of the beaters striking the same it is not liable to break the beaters,

and they are flexible enough to give under the stroke of the beaters. The side rails of the frame are supported near their outer ends by means of supporting - legs 50, pivotally attached to the members or sections 35 of the rails. In order to drive all dust and foreign matter away from the carpet as it is extracted and toward the rear of the frame, I provide a fan 51, journaled in bearings 52, suspended from the underneath face of the sections or members 35, a pulley 53 being mounted on the shaft of this fan and connected by cord or belt 54 with a pulley 55 on the beater-actuating shaft 7.

In operation the frame is extended and the supporting-frames swung out to the supporting position to receive the carpet. The carpet is placed in a roll on one of the supporting-frames and drawn across the supporting-bed. For convenience in drawing the carpet across the supporting-bed the beaters may be held elevated, which is readily accomplished by depressing lever 27, so as to force presser-bar 25 into engagement with the sections or members 12, depressing the front ends of said beaters and elevating their outer ends, the lever being held by engaging hook 29 in eye 30. When the carpet has been positioned, the presser - bar is then released and rotary motion imparted to shaft 7. This causes the cams or knockers to engage the upper faces of the sections or members 12 of the beaters near their forward ends and elevate the outer ends of the beaters. As the cams or knockers pass out of engagement with the sections or members 12 of the beaters the latter are drawn down rapidly under the action of the springs 20 and strike the carpet with considerable force to drive out the dust and other foreign substance. The cams or knockers are so placed on the shaft as to alternately engage with the beaters, and two cams or knockers are provided for each beater, whereby the latter will be given two strokes with each revolution by the shaft. The dust as it is beat out of the carpet is expelled toward the rear of the frame of the fan, thus preventing the same from settling again in the carpet or inconveniencing the operator. The carpet as it is drawn across the rollers 48 and bed 49 is supported on the opposite supporting-frame and is therefore not subjected to any of the dust driven down through the carpet by the beaters. In the present illustration I have shown but three beaters; but of course this number may be increased, if desired.

When the machine is not in use it may be folded in a comparatively compact form by simply slackening up nuts 42, folding up the carpet-supporting frames at the sides of the side rails, and sliding back clips 37 past the joint between sections 34 and 35, whereby said sections may be folded in the manner shown in Fig. 5. The supporting-legs 50 fold up against the sections or members 35 of the side rails, and as the bars 43 are pivotally connected to the sections 35 they may be

folded against the same when hooks 46 are detached, while each of the legs 45 being pivoted to one of the bars 43 this leg can be folded up with the folding of bars 43 and bars 44.

While I have herein shown and described the invention in detail as it is practiced by me, yet it will be observed that in the construction of the machine various changes may be made in the details of construction without departing from the general spirit of my invention.

Having fully described my invention, what I claim as new, and desire to secure by Letters Patent, is—

1. In a carpet-beating machine, the combination of a pair of housings or standards, slotted side rails adjustably secured to said housings or standards, a supporting - bed carried by said side rails, supporting-frames pivoted to the side rails, supporting - legs pivoted to said rails, a plurality of beaters mounted on a shaft journaled in the housings or standards, an actuating - shaft journaled in said housings or standards, cams or knockers carried by said shaft for engagement with the beaters for vibrating the same, and means

for operating said actuating - shaft, substantially as described.

2. The combination with a plurality of pivoted beaters, and means for operating the said beaters, and means for forcing the said beaters down to engagement with the carpet, said means comprising a regulating-bar pivoted at one end, springs connected to said bar and beaters respectively, and means connected to the unpivoted end of said bar for adjusting the same.

3. In combination with the beaters and means for supporting the same, means for elevating the said beaters, a pressure-bar, a rod connected to said bar and being mounted in a supporting means, a lever pivoted to said rod and to the supporting means, means for holding said lever in a lowered position, and means for elevating said lever when it is released.

In testimony whereof I affix my signature in the presence of two witnesses.

JOSEP LEWANDOWFSKI.
